UNITED STATES PATENT OFFICE

2,601,747

GRINDING APPARATUS

Edwin A. Nichols, Springfield, Mass., assignor
to American Bosch Corporation, Springfield,
Mass., a corporation of New York

Application March 31, 1949, Serial No. 84,639

3 Claims. (Cl. 51—95)

1

This invention relates to grinding apparatus and has particular reference to new and improved apparatus for grinding or forming accurate leads or edges on parts of precision apparatus such as fuel injection apparatus.

An object of the invention is to provide a new and improved apparatus of the type set forth which is particularly adapted for accurately forming parts that require a high degree of accuracy such as the plungers of fuel injection apparatus.

Another object of the invention is to provide a new and improved apparatus for forming the helix or metering edge on the plungers of fuel injection apparatus.

Another object of the invention is to provide a new and improved apparatus for forming an accurate lead on a cylindrical surface.

Another object of the invention is to provide a device of the type set forth which employs a relatively large grinding wheel.

Another object of the invention is to provide a new and improved device for forming an accurate helical lead on a cylindrical surface using as large a grinding wheel as possible for high surface speed.

Another object of the invention is to provide a device of the type set forth which is relatively simple and economical in construction yet efficient in operation.

Other objects and advantages of the invention will be apparent from the following description taken in connection with the accompanying drawings. It will be understood that changes may be made in the details of construction and arrangement of parts without departing from the scope of the invention as expressed in the accompanying claims, as the preferred form has been given by way of illustration only.

Referring to the drawings:

Fig. 1 is a front view of one form of a device embodying the invention;

Fig. 2 is a top or plan view thereof;

Fig. 3 is an end view thereof;

Fig. 4 is a fragmentary sectional view taken on line 4—4 of Fig. 2 looking in the direction of the arrows;

Fig. 5 is a fragmentary sectional view taken on line 5—5 of Fig. 2 looking in the direction of the arrows;

Fig. 6 is a fragmentary sectional view taken on line 6—6 of Fig. 1 looking in the direction of the arrows;

Fig. 7 is a fragmentary sectional view taken on line 7—7 of Fig. 2 looking in the direction of the arrows;

Fig. 8 is a fragmentary sectional view taken on line 8—8 of Fig. 2 looking in the direction of the arrows;

Fig. 9 is a side view of a part for fuel injection

2

apparatus before the forming thereon of the metering edge;

Fig. 10 is a fragmentary view similar to Fig. 9 but on an enlarged scale;

Fig. 11 is a view showing the positions of the plunger and grinding wheel during the forming of the metering edge on the plunger; and

Fig. 12 is a fragmentary view generally similar to Fig. 11 but on an enlarged scale.

10 The device embodying the invention comprises broadly, a support for the work which is to have an accurate lead ground thereon such as a plunger for fuel injection apparatus, a cutter such as a grinding wheel and means for moving said cutter and work relative to each other in such manner that an accurate lead will be formed on the work. The actuating means may be hydraulic or mechanical and in the construction shown by way of illustration consists of a hydraulically actuated work support adapted to move the work in a helical cam controlled path relative to the grinding wheel whereby an accurate helical metering lead will be formed on the plunger.

15 Referring more particularly to the drawings wherein similar reference characters designate corresponding parts throughout the several views, the device shown embodying the invention comprises a base 1 supporting the grinding head 2 on which is mounted the grinding wheel 3 for rotation in the usual manner. The grinding wheel is preferably fixed relative to the work and preferably the wheel employed has an angular surface on its periphery which angle is the 20 difference between the angular relation of the work and the grinding wheel.

The grinder 1 and grinding head 2 shown are of conventional design and other conventional design grinding machines may be employed.

25 On the grinder 1 is supported the base 4 on which is mounted the carriage 5 for longitudinal movement thereon as hereinafter described and which is provided with the cam drum 6 and cam 7. The cam 7 is secured to the cam drum 6 by means of bolts or the like 8 which may be removed to allow the positioning of various cams on the cam drum depending upon the part to be formed. It will be noted from the drawing that the diameter of the cam 7 is many times as great as the diameter of the work piece or plunger 18 on which the metering lead is to be formed. This minimizes greatly any errors in the finished lead.

30 The carriage 5 is provided with openings 9 adjacent its opposite ends and across each of which extend a pair of spaced guide bars 10, each of which extends through a sleeve or bushing 11.

The guide bars 10 are adapted to extend through bushings 11 extending through projections 12 on the base 4.

In this manner the carriage 5 is mounted for longitudinal movement on the base 4 and the extent of such movement is controlled by the size of the openings 9 and the length of the sleeves 10 as shown in Fig. 4.

The cylinder 13 is secured to the end of the carriage 5 and is adapted to receive the piston 14 which is secured to the projection 12 on the base 4 by means of the connector 15 which is secured to said projection 12. The connector 15 is positioned between the pair of sleeves 10 and also is preferably positioned substantially in alignment therewith.

The cylinder 13 is connected by line 38 through a two-way check valve to a fluid supply and line 39 also is connected to a suitable fluid supply whereby a uniform pressure is maintained in cylinder 13 throughout the stroke of piston 14 in both directions and line 38 supplies fluid to the cylinder 13 on the return stroke of carriage 5 and maintains back pressure throughout the forward stroke of carriage 5. It will be seen that the position of the piston 14 is fixed relative to the base 4 as it is connected thereto by connector 15 and that the cylinder which is fixed on carriage 5 reciprocates with said carriage upon the reciprocation thereof.

On the carriage 5 is positioned the adjustable supporting member 35 carrying the centering pin 16 which is resiliently urged by the spring 17 for maintaining the workpiece 18 in aligned relation and the other end of said workpiece 18 is secured in the chuck 19. The support 35 is slideable on the slide 36 on carriage 5 and is adapted to be locked in adjusted position by set screws 37.

The cam 7 and cam drum 6 are adapted to be rotated by the hydraulic motor 20 which is coupled with the drive coupling 21 by means of the member 22 which is connected to the rotor 23 of the motor 20 at one end and has its opposite end keyed to the drive coupling 21 by means of the woodruff key 24.

The hydraulic motor 20 is of the eccentric vane type and includes the vane 25 and springs 26. The motor 20 is provided with the stuff box gland 27 and packing 28.

The hydraulic motor 20 is connected to the fluid inlet line 41 and fluid outlet line 42, although it is reversible by changing line 41 to an outlet line and line 42 to an inlet line.

The cam 7 is adjustable longitudinally together with carriage 5 to position the work in desired relation with grinding wheel 3 by means of micrometer screw 44 which may carry indicia which may be read against indicator 45, and adjustment of micrometer screw 44 adjusts the position of stop or cam follower 46 which abuts the face 40 of cam 7 when said cam is at the beginning of its working position. As cam 7 rotates against follower 46, the carriage 5 is reciprocated and work piece 18 which is carried by chuck 19 is simultaneously reciprocated and rotated relative to grinding wheel 3 which forms the metering lead on the plunger as hereinafter described.

The drive coupling 21 is provided with the coupling cushioning blocks 29.

The cam drum 6 is keyed to the shaft 30 which is journaled in the ball bearings 31 and 32 in the housing 33 which is supported on the carriage 5 and adapted to be moved longitudinally therewith.

On the end of the shaft 30 is provided the centering chuck 19 for retaining the workpiece 18 in

operative position in cooperation with centering pin 16.

The device of the present invention is particularly adapted to form or grind accurate helical leads on a cylindrical surface using as large a wheel as possible for high surface speed, and is particularly adapted for the forming of accurate helical metering leads on the plungers of fuel injection apparatus as shown in the drawings.

In forming such plungers the blank is milled away at 47 to form the helical lead or shoulder 48 as shown in Fig. 10, and by using the machine of this invention the bevelled helical lead 49 is formed on the edge of the lead 48 with the lead 49 being of required accuracy.

In Fig. 9 a side view of a complete plunger blank is shown prior to the forming of the helical lead thereon and in Fig. 10, the portion of the plunger 18 on which the bevelled lead 49 is to be formed is shown on an enlarged scale.

In Fig. 11, the relative positions of the plunger and grinding wheel are shown and in Fig. 12 this is shown on an enlarged scale. The surface on the edge of the grinding wheel 3 may be of desired angle and preferably the center of the wheel is placed above the center line of the work 18.

In operation, the work 18 is positioned between the center 16 and chuck 19 and the micrometer screw 44 adjusted to properly position the work 18 relative to the grinding wheel 3.

The cylinder 13 and piston 14 then are brought into action to cause longitudinal reciprocation of the carrier 5 and work 18 relative to said grinding wheel 3 and simultaneously with the reciprocation of said carrier 5, the hydraulic motor 20 is caused to rotate and being connected to the work support, therefore, causes simultaneous rotation of the work 18 thereby causing the work 18 and grinding wheel to engage over the desired portion of the helical lead 48 whereby the accurately formed bevelled lead screw 49 will be formed on the edge of the lead 48.

From the foregoing it will be seen that I have provided means for obtaining all of the objects and advantages of the invention.

Having described my invention, I claim:

1. In a device of the character described, a grinding wheel, a reciprocating work supporting carriage having a pair of spaced work supports adapted to support a work piece relative to said grinding wheel and to be movable axially and rotatably, a cam follower and a rotatable face cam engaging said follower on said support and substantially axially aligned with said work supports and adapted to move said work support and work piece relative to said cutter, hydraulic means for reciprocating said carriage and hydraulic means for operating said cam.

2. In a device of the character described, a grinding wheel, a reciprocating work supporting carriage having a pair of spaced work supports adapted to support a work piece relative to said grinding wheel and to be movable axially and rotatably, a cam follower and a rotatable face cam engaging said follower on said support and substantially axially aligned with said work supports and adapted to move said work support and work piece relative to said grinding wheel and hydraulic means for operating said cam and reciprocating said carriage, said grinding wheel being supported in angular relation with the work piece with the difference between the angular relation of the work piece and face of the

grinding wheel being the angle formed on the periphery of the grinding wheel.

3. In a device of the character described, a cutter, a reciprocating work supporting carriage having a pair of spaced work supports adapted to movably support a work piece relative to said cutter and to be movable axially and rotatably, a cam follower and a rotatable face cam engaging said follower on said support and substantially axially aligned with said work supports and 10 adapted to move said work support and work piece relative to said cutter, and hydraulic means for actuating said cam and reciprocating said work support and hydraulic means creating a constant load against which said work support is 15 positioned by said cam.

EDWIN A. NICHOLS.
